Attorney.

UNITED STATES PATENT OFFICE.

FREDERICK C. SIMMONS, OF HIGHLAND PARK, PENNSYLVANIA, ASSIGNOR TO PIONEER SUSPENDER COMPANY, A CORPORATION OF PENNSYLVANIA.

BELT.

Application filed June 17, 1924. Serial No. 720,532.

To all whom it may concern:

Be it known that I, FREDERICK C. SIMMONS, a citizen of the United States, residing at Highland Park, in the county of 5 Delaware, State of Pennsylvania, have invented a new and useful Belt, of which the following is a specification.

My invention relates to improvement in belts, especially to that type of belt in which 10 retaining loops are provided for securing the free end of the belt, after the same has passed through the buckle. Two retaining loops are usually employed, and these, in general practice, are secured loosely by a 15 narrow strip of leather or similar material, connected to the main body of the belt. This narrow strip is usually attached to the belt at separated points by elements of the 20 post and socket devices which disengageably secure the main body of the belt with the turned over end of the belt which forms the buckle loop. The distance between the 25 points of attachment of the two post and socket devices forms the limit of adjustment of one retaining loop which is secured between the strip and the belt and between 30 said two points of attachment. The other retaining loop is secured by a loop formation of the narrow strip which extends beyond one of the said fastening devices. The 35 tension of the narrow strip between the two points of attachment and the friction between the strip and the substantially rigid adjacent wall of the belt, tend to maintain the retaining loop thereby secured in any desired position of adjustment. The long and unsecured loop of the narrow strip, which extends beyond or outside the two 40 fastening devices and secures the other retaining loop, provides no such tension or friction for holding its retaining loop in position of adjustment. It merely serves to prevent its moving beyond a maximum distance from the other retaining loop. It does 45 not prevent the two retaining loops from approaching too close together for useful service. One of the objects of my invention is to provide means for overcoming this disadvantage. The other object is to utilize 50 such means for indicating the size of the belt, the trade-mark or the like.

Referring to the drawings which illustrate merely by way of example a suitable embodiment of the invention—

Fig. 1 is a front view of the end of the belt 55 to which the buckle is attached.

Fig. 2 is a perspective view of same with the post and socket fasteners separated and the buckle removed.

Fig. 2a shows in plan and elevation on 60 enlarged scale, the size and trade-mark attachment or rivet member.

Fig. 3 is an edge view of the end of the belt enlarged.

Similar numerals refer to similar parts 65 throughout the several views.

The main body 4 of the belt is formed with the return bend or loop 5 for securing the buckle 6. The bent-over part 7 is disengageably secured to the main body 4 by 70 the post and socket fasteners 8, 8'. The retaining loops 9 and 10 are threaded on the main body 4. Loop 9 is secured between a narrow strip 11, and the belt body 4, and between the fasteners 8. The tension of this 75 strip 11 is such that, in cooperation with the comparatively stiff or rigid body 4, that the loop 9 is held in any desired position of adjustment. The retaining loop 10 is engaged by an extension of strip 11 passing beyond 80 a fastener 8 and returning back and secured upon itself and the body 4 by said fastener 8, thus forming a loop formation 12 of this extension of strip 11. When this loop formation 12 is entirely open, as is the usual 85 practice, there is nothing to prevent the retaining loop 10 from sliding along the body portion 4 to and from the fastener 8 and to and from the end of said loop formation 12. Thus the two retaining loops 9 and 10 may 90 be brought accidentally into close juxtaposition, which is objectionable.

In accordance with the present invention however, the two extensions of the folded over portion 12 are secured together at a 95 point, as at 13, in close proximity to the retaining loop 10, when the same is at the extreme outer end of loop formation 12. By this means a close fitting pocket is provided for loop 10, whereby little or no play is permitted of the retaining loop member 10 in the loop formation 12, and thus the retaining loops 9 and 10, when the belt is pressed flat against the body of the wearer are normally kept a substantial distance apart. 100 The means for securing the two parts of strip 11 together at point 13 comprises a rivet member or similar device provided, 105

with a head or disc 14 upon which may be displayed the size number of the belt, the trade-mark the name of the maker or similar device. The disc 14 is provided with a stem 5 or shank 15 which passes through both extensions of strip 11 and is clinched on the underside thereof as at 16, as clearly shown in Fig. 3.

In order also to increase the stability of 10 the position of the retaining loop 10 in respect to the belt and to cover more completely the means for fastening the two ends of the strap forming the said loop 10, the portion of the strip 11 which comprises the loop 15 formation 12, is increased in width to substantially the width of the belt, so that nearly the entire underside of the retaining loop 10 is covered thereby. This wide part tapers from the rivet members 14 and 15 to the 20 narrow dimension of the balance of the strip 11. It will be noted that the rear side of retaining loop 9 is covered by the turned over portion 7 of full belt width.

What I claim is:—

25 1. The combination of a belt having a bent over end to form the buckle engaging loop, fastening devices for securing said bent over end to the main body of the belt, retaining loops for the other end of the belt 30 which projects through the buckle, means for securing said retaining loops loosely to the main body of the belt, comprising a flexible strip secured to the belt by elements of

said fastening devices, one retaining loop secured between said strip and belt and between said fastening elements, said flexible strip having a substantial extension beyond a fastening element and having a folded over part, the layers of which are secured together at a distance from the bend corresponding approximately with the width of the retaining loop to form a pocket for securing and maintaining the other retaining loop at the extreme end of the said folded portion. 40

2. The combination of a belt having a bent over end to form the buckle engaging loop, fastening devices for securing said bent over end to the main body of the belt, retaining loops for the other end of the belt which projects through the buckle, means for securing said retaining loops loosely to the main body of the belt, comprising a flexible strip connected to the body of the belt by said fastening devices with one retaining 50 loop between the strip and the belt and two said fastening devices, the other retaining loop secured by a loop formation of said flexible strip projecting beyond one of said fastening devices, and a body having a display disc and a rivet stem for securing together the two extensions of the loop formation at a point distant from the end of the loop formation corresponding approximately with the width of the retaining loop. 55

FREDERICK C. SIMMONS.
